UNITED STATES PATENT OFFICE.

CHARLES DOUGLAS, OF DETROIT, MICHIGAN.

BROOM.

SPECIFICATION forming part of Letters Patent No. 299,059, dated May 20, 1884.

Application filed December 27, 1882. (No model.)

To all whom it may concern:

Be it known that I, CHARLES DOUGLAS, of Detroit, county of Wayne, State of Michigan, have invented a new and useful Improvement 5 in Brooms; and I declare the following to be a full, clear, and exact description of the same, such as will enable others skilled in the art to which it pertains to make and use it, reference being had to the accompanying drawings, which form a part of this specification.

This invention relates to certain improvements in the manufacture of brooms, and is designed more particularly as an improvement 15 upon the invention shown and described in the Letters Patent granted to me, bearing date the 28th day of August, 1883, and numbered 283,979.

The nature of my invention consists in the improved construction and arrangement of 20 parts hereinafter fully described, and specifically pointed out in the claim.

Referring to the accompanying drawings, Figure 1 is a sectional view of the handle-socket detached from the broom, and Fig. 2 a 25 central sectional view of a broom complete constructed according to my invention.

In said drawings, A designates the handle-socket, having an annular exterior groove or recess, a', and tapered interiorly for the reception of the handle B, and is secured to the 30 broom-head D in any suitable manner. The broom-head D is preferably made of wood, and is hollowed out or recessed between its ends, for the purpose of forming a space for the 35 reception of a portion of the broom-corn.

E is a clamp, which is held securely against the head D by means of wires or fastenings E', whereby the interposed broom-corn between the head and clamp is held securely in place. A portion of the corn, which constitutes the outer portion of the broom proper, is carried up around the head D and socket A, to which latter it is secured by means of a suitable wrapping of wire or twine.

It will be seen that the annular groove or recess a' in the socket forms an important feature of my invention, as by its use the corn is held more securely to the socket than it could be when a plain socket, such as shown in my patent above mentioned, is employed.

Having thus described my invention, what I claim is—

The broom consisting of the combination, with the head and clamp constructed as shown, and secured together by means of wires or 55 fastenings, of the handle-socket having an interior tapering orifice and an exterior annular groove, a removable handle adapted to be received in said socket, and the broom-straw, a portion of which is held between the head and 60 clamp, and a portion thereof brought around the head and fastened about said socket by a suitable wrapping of wire or twine, substantially as described.

In testimony whereof I sign this specification in the presence of two witnesses.

CHARLES DOUGLAS.
